ATTACHMENT FOR SEWING MACHINES

Filed April 28, 1937

UNITED STATES PATENT OFFICE

2,134,010

ATTACHMENT FOR SEWING MACHINES

Alexander Soltan, Elmhurst, N. Y., assignor to
Percy W. Valentine, Brooklyn, N. Y.

Application April 28, 1937, Serial No. 139,486

20 Claims. (Cl. 112—62)

This invention relates to an attachment for sewing machines of the kind employed for sewing the soles of shoes to the uppers, and the object of the invention is to provide an attachment 5 of the class described having means for engaging and supporting a sole as well as the upper in the operation of stitching the upper to a welt lip formed on the sole, while maintaining the sole in a substantially vertical position and especially in the formation of what is known 10 as inturned shoes; a further object being to provide an attachment of the class described employing a supporting member or spreader adapted to operate in the channel formed within the 15 integral flange or welt in the stitching operation, and further wherein said support is rotatable to provide a freer movement of the sole in the stitching operation; a further object being to provide tensional means on the attachment 20 cooperating with the presser-foot of the machine to aid in supporting the upper in connection with said flange in the stitching operation; a further object being to provide an attachment employing a folding arm or horn, freely adjust- 25 able toward and from the spreader, and having a rotatable disc or wheel at the free end portion thereof, providing free action of the sole and upper through and between the spreader and wheel in the stitching operation; a further ob- 30 ject being to provide means for adjusting the vertical and lateral positions of said arm, and with these and other objects in view the invention consists in a device of the class and for the purpose specified which is strong and durable, as 35 well as simple in construction and efficient in use, and which is constructed as more fully hereinafter described and claimed.

The invention is fully disclosed in the following specification, of which the accompanying 40 drawing forms a part, in which the separate parts of my improvement are designated by suitable reference characters in each of the views, and in which

Fig. 1 is a perspective view of an attachment 45 made according to my invention.

Fig. 2 is a partial section on the line 2—2 of Fig. 1 with part of the construction shown in elevation.

Fig. 3 is a section on the line 3—3 of Fig. 2; and 50

Fig. 4 is a section on the line 4—4 of Fig. 1.

This application forms an improvement on the structure shown and described in a prior patent granted to me July 7, 1936, No. 2,046,493, and in the accompanying drawing I have eliminated the stitching mechanism of the machine 55

in order to simplify the illustration, but it will be understood that my improved attachment will be applicable to sewing machines in the manner diagrammatically illustrated in said patent.

In Fig. 1 of the drawing I have indicated at 5 5 a supporting bracket or base of the attachment having a lower L-shaped portion 6 to facilitate mounting of the attachment in connection with a sewing machine of the type and kind under consideration. The upper end portion 7 of the 10 bracket is U-shaped in cross-sectional form and the inner adjacent surfaces of the side walls of the portion 7 are provided with beveled lateral projections 8 for adjustably supporting a block or bar 9 in the bracket, said block having angular 15 flanges 10 at the sides thereof cooperating with the projections 8, the block being retained in different positions of adjustment by a bolt 11 serving to draw opposed walls of the part 7 together. 20

The rear end portion of the block 9 is recessed as seen at 12, the recess being arranged above a downwardly and rearwardly projecting supporting plate 13 integral with the block 9 in the construction shown. Rotatably mounted in the 25 forward end portion of the block 9 is a freely rotatable shaft 14 having an enlarged beveled disc 15 at the outer end thereof, the inner end of the shaft 14 having an adjustment lock-ring 17 provided with a set screw 18 for retaining the shaft 30 against movement in one direction in said block, the shaft having a collar portion 19 adjacent the head 15 for limiting inward movement of the shaft in said block. It will appear that the ring 17 is disposed in a recess in the block 9 and 35 the shaft 14 is arranged so as to permit the outer flat surface 15a of the head 15 to clear the needle mechanism and to act as a guide and reinforcement for the needle in the stitching operation as it travels upwardly in front of the 40 surface 15a. The shaft 14 is arranged at an angle in the block 9. 45

Arranged upon the plate 13 is a supplemental block 20 in which is mounted the rod 21 of a folding arm or horn 22 having an outer yoke-shaped portion 23 in the channel or recess 24 of which the sole and upper are free to pass. The free end portion 25 of the yoke-shaped end 23 of the arm, is extended to a position forwardly of the head 15 which forms the spreader, of the 50 attachment, and on said end 25 is mounted a disc or wheel 26 which is freely rotatable in its support and cooperates with the spreader to support the sole and upper in proper positions in the stitching operation. The arm 22 is adjustable 55

by means of an knurled nut 27 to regulate the position of the roller 26 with respect to the spreader 15 to compensate for work-pieces of different thicknesses. The arm 22 has an offset 5 22a therein which extends from the forward end of the attachment and to permit free swinging movement of the arm or member 22 on the axis provided by said rod.

The shank of the nut 27 is provided with an 10 annular projecting flange 28 which operates in a groove 29 formed in the block 20 to retain the nut against movement in the block and to provide for forward and backward adjustment of the member 22 for reasons above stated. At 27a 15 I have shown a knurled lock nut for retaining the member 22 in different positions of adjustment. I also provide means for regulating the height of the unit, consisting of the member 22 and the block 20, and associated parts. This means consists of four vertically adjustable screws 30, 20 disposed in the corner portions of the plate 13 and adapted to engage the lower surface of the supplemental block 20 and a lock or coupling screw 31 having a knurled head 31a, for securing the block 25 20 in position on the plate 13. With this construction it will appear that the height of the disc or wheel 26 with respect to the spreader 15, may be varied to compensate for different kinds of work-pieces.

30 I also provide means for adjusting the wheel laterally for proper alinement with the spreader 15, which consists of attaching a plate 32 to one 35 side of the supplemental block 20 in such manner as to project below the block 20 and to overlie the adjacent side edge portion of the plate 13, and to arrange two milled screws 33 in the end portions of the plate 32 forwardly and rearwardly of the screw 31 so as to swing the block 20 on the screw 31 as a fulcrum or pivot to move the wheel 40 26 transversely of the spreader 15. It will be understood that the movement of the block 20 at the pivot 31 will be slight as compared with the movement contributed to the wheel 26. When the desired adjustments have been made with regard to the vertical and lateral positions of the wheel 26, the screw 31a will be tightened.

Arranged upon the top of the block 9 at the forward end thereof, is a plate 34 having an upwardly projecting rounded stop 35 and at one side 50 of the plate 34 is an elongated bar 36, the forward end portion 37 of which is undercut to correspond with an undercut portion 9a on the block 9 to provide clearance for the flange or welt lip 38 on the sole 39 as well as that part of the upper 55 including the lining therefor as indicated at 40 in Fig. 2 of the drawing. The bar 36 has a laterally extending pivot pin 41 upon which is pivoted a pawl 42, the forward upwardly and outwardly curved end 43 of which is normally held 60 in raised position by a flat spring 44 arranged upon the screw 45, employed for holding the bar 36 in position. It will be understood that the bar 36 is recessed to receive the pawl 42. This bar has an elongated aperture 46 through which the screw 45 passes to provide front and rear adjustment of the bar as well as the pawl 42, which is movable therewith so as to adjust the position of the end 43 of the pawl and the end 37 of the bar with respect to the undercut 9a.

70 It will be understood that the end 43 of the pawl 42 is disposed in position to be engaged by the presser-foot of the sewing machine in the stitching operation, and will serve to support the flange 38 and that part of the upper at 40 in firm 75 engagement with each other in the stitching op-

eration. Or in other words, will insure a more proper alinement of the parts, and to tensionally hold the parts together at the beginning of the stitching operation.

At 47 I have shown a vertically adjustable screw 5 which operates in connection with the cross-head 22a to limit the downward swinging movement of the arm 22 or the wheel 26 thereon.

From a consideration of Fig. 2 of the drawing it will appear that the sole and upper are stitched 10 together while the sole is supported in a substantially vertical position, and it will appear that the spreader 15 enters the channel or recess 39a of the sole 39 under the flange 38, and to support the flange in extended position to provide for the 15 stitching operation. It will be understood also, that as the sole 39 is moved between the spreader 15, and wheel 26, both of said parts are free to rotate so as to eliminate the binding of the sole and the upper between said parts. In other words 20 to provide a free movement of the work-pieces therebetween.

It will be apparent that by virtue of the several adjustments provided, my attachment is adaptable for use in connection with work-pieces 25 of varying dimensions as well as in different sizes and constructions, and especially with respect to different kinds of welts which may be employed.

Having fully described my invention, what I claim as new and desire to secure by Letters 30 Patent, is:

1. An attachment for sewing machines of the class described, for supporting the sole and upper in the operation of stitching the same together, said attachment comprising a rotatable spreader 25 adapted to engage and support the welt lip of the sole, and means involving a swinging arm having a work-piece engaging part adjustable toward and from said spreader for supporting the sole and the upper in position in the operation of 40 stitching the same together.

2. An attachment for sewing machines of the class described, for supporting the sole and upper in the operation of stitching the same together, said attachment comprising a rotatable spreader 45 adapted to engage and support the welt lip of the sole, means involving a swinging arm having a rotatable work-piece engaging part adjustable toward and from said spreader for supporting the sole and the upper in position in the operation of 50 stitching the same together, and means for adjusting said arm and the part thereon laterally to aline said part with said spreader.

3. An attachment for sewing machines of the class described, for supporting the sole and upper 55 in the operation of stitching the same together, said attachment comprising a spreader adapted to engage and support the welt lip of the sole, means involving a swinging arm having a work-piece engaging part adjustable toward and from 60 said spreader for supporting the sole and the upper in position in the operation of stitching the same together, means for adjusting said arm and the part thereon laterally to aline said part with said spreader, and other means for adjusting said 65 arm and part vertically.

4. An attachment for sewing machines of the class described, for supporting the sole and upper in the operation of stitching the same together, said attachment comprising a spreader 70 adapted to engage and support the welt lip of the sole, means involving a swinging arm having a work-piece engaging part adjustable toward and from said spreader for supporting the sole and the upper in position in the operation of 75

- stitching the same together, means for adjusting said arm and the part thereon laterally to align said part with said spreader, other means for adjusting said arm and part vertically, said spreader being rotatable in its support, and the part on said arm being rotatable to provide free movement of the work-piece between said part and rotatable spreader. 5
5. An attachment for sewing machines of the class described, for supporting the sole and upper in the operation of stitching the same together, said attachment comprising a spreader adapted to engage and support the welt lip of the sole, means involving a swinging arm having a work-piece engaging part adjustable toward and from said spreader for supporting the sole and the upper in position in the operation of stitching the same together, means for adjusting said arm and the part thereon laterally to align said part with said spreader, other means for adjusting said arm and part vertically, said spreader being rotatable in its support, the part on said arm being rotatable to provide free movement of the work-piece between said part and 15 rotatable spreader, and spring actuated means arranged in close proximity to said spreader to aid in supporting the work-pieces in connection with said spreader. 20
6. An attachment for use in supporting the sole and upper in the operation of stitching the same together, said attachment comprising a block, means for adjustably mounting said block in a suitable support, a spreader at one end of the block for engaging and supporting the sole in the operation of stitching the same, and means 25 movably and adjustably supported in connection with said block and having a rotatable part adapted to be arranged in close proximity to said spreader to aid in the support of the sole and upper in the operation of stitching said parts together. 30
7. An attachment for use in supporting the sole and upper in the operation of stitching the same together, said attachment comprising a block, means for adjustably mounting said block in a suitable support, a spreader at one end of the block for engaging and supporting the sole in the operation of stitching the same, means 35 adjustably supported in connection with said block and having a part arranged in close proximity to said spreader to aid in the support of the sole and upper in the operation of stitching said parts together, means for adjusting said last named means vertically in said block and for retaining the same in different positions of adjustment. 40
8. An attachment for use in supporting the sole and upper in the operation of stitching the same together, said attachment comprising a block, means for adjustably mounting said block in a suitable support, a spreader at one end of the block for engaging and supporting the sole in the operation of stitching the same, means 45 adjustably supported in connection with said block and having a part arranged in close proximity to said spreader to aid in the support of the sole and upper in the operation of stitching said parts together, means for adjusting said last named means laterally in said block to regulate the position of the part on said means with respect to said spreader, and means for adjusting said part toward and from the spreader, and means for adjusting said part in the different positions of adjustment thereof. 50
9. An attachment for use in supporting the sole and upper in the operation of stitching the same together, said attachment comprising a block, 55
- means for adjustably mounting said block in a suitable support, a spreader at one end of the block for engaging and supporting the sole in the operation of stitching the same, means adjustably supported in connection with said block and having a part arranged in close proximity to said spreader to aid in the support of the sole and upper in the operation of stitching said parts together, means for adjusting said last named means laterally in said block to regulate the position of the part on said means with respect to said spreader, means for adjusting said part toward and from the spreader, and said last named means comprising a shaft, a rod, forming a pivot to provide swinging movement of said part in the different positions of adjustment thereof. 60
10. An attachment for use in supporting the sole and upper in the operation of stitching the same together, said attachment comprising a block, means for adjustably mounting said block in a suitable support, a spreader at one end of the block for engaging and supporting the sole in the operation of stitching the same, means 65 adjustably supported in connection with said block and having a part arranged in close proximity to said spreader to aid in the support of the sole and upper in the operation of stitching said parts together, means for adjusting said last named means laterally in said block to regulate the position of the part on said means with respect to said spreader, means for adjusting said part toward and from the spreader, said last named means comprising a shaft, a rod, forming a pivot to provide swinging movement of said part in the different positions of adjustment thereof, and spring control means in juxtaposition to said spreader to aid in supporting the sole and upper in position during the stitching operation thereof. 70
11. An attachment for use in supporting the sole and upper in the operation of stitching the same together, said attachment comprising a block, means for adjustably mounting said block in a suitable support, a spreader at one end of the block for engaging and supporting the sole in the operation of stitching the same, means 75 adjustably supported in connection with said block and having a part arranged in close proximity to said spreader to aid in the support of the sole and upper in the operation of stitching said parts together, means for adjusting said last named means laterally in said block to regulate the position of the part on said means with respect to said spreader, means for adjusting said part toward and from the spreader, said last named means comprising a shaft, a rod, forming a pivot to provide swinging movement of said part in the different positions of adjustment thereof, and adjustable means for limiting the swinging movement of said part in one direction. 80
12. A device of the class described comprising a yoke-shaped supporting bracket, a block adjustably mounted within the yoke of said bracket, a work-piece supporting member at one end of said block, a swinging work-piece supporting part on said block and arranged in close proximity to said member, and means for adjusting said part longitudinally of the block toward and from said member to compensate for work-pieces of different thicknesses to be supported between said member and part. 85
13. A device of the class described comprising a yoke-shaped supporting bracket, a block adjustably mounted within the yoke of said bracket. 90

et, a work-piece supporting member at one end of said block, a swinging work-piece supporting part on said block and arranged in close proximity to said member, means for adjusting said part longitudinally of the block toward and from said member to compensate for work-pieces of different thicknesses to be supported between said member and part, and a spring actuated work-piece supporting element mounted in said block and arranged in close proximity to said member to aid in supporting a work-piece in connection with said member.

14. A device of the class described comprising a yoke-shaped supporting bracket, a block adjustably mounted within the yoke of said bracket, a work-piece supporting member at one end of said block, a swinging work-piece supporting part on said block and arranged in close proximity to said member, means for adjusting said part longitudinally of the block toward and from said member to compensate for work-pieces of different thicknesses to be supported between said member and part, a spring actuated work-piece supporting element mounted in said block and arranged in close proximity to said member to aid in supporting a work-piece in connection with said member, and said element being adjustable longitudinally of said block.

15. A device of the class described comprising a yoke-shaped supporting bracket, a block adjustably mounted within the yoke of said bracket, a work-piece supporting member at one end of said block, a swinging work-piece supporting part on said block and arranged in close proximity to said member, and means involving independently adjustable devices for adjusting said part toward and from, and laterally and vertically with respect to, said member.

16. A device of the class described comprising a yoke-shaped supporting bracket, a block adjustably mounted within the yoke of said bracket, a work-piece supporting member at one end of said block, a swinging work-piece supporting part on said block and arranged in close proximity to said member, means involving independently adjustable devices for adjusting said part toward and from, and laterally and vertically with respect to, said member, and means involving a yieldable element arranged in close proximity to said member to aid in supporting a work-piece in connection therewith.

17. A device of the class described comprising a yoke-shaped supporting bracket, a block adjustably mounted within the yoke of said bracket, a work-piece supporting member at one end of said block, a swinging work-piece supporting part on said block and arranged in close proximity to said member, means involving independ-

ently adjustable devices for adjusting said part toward and from, and laterally and vertically with respect to, said member, means involving a yieldable element arranged in close proximity to said member to aid in supporting a work-piece in connection therewith, and said part having a yoke-shaped portion arranged at one side of and in alinement with said member.

18. A device of the class described comprising an elongated block having a work-piece supporting member at one end thereof, a supplemental block adjustably supported in connection with the other end of the first named block, a yoke-shaped arm arranged at one side of the block and coupled with the supplemental block to provide swinging movement of the arm with respect to the first named block, the free end of said arm having a work-piece supporting part arranged in close proximity to said member, and means for adjusting said arm longitudinally of the supplemental block to adjust the part thereon toward and from said member.

19. A device of the class described comprising an elongated block having a work-piece supporting member at one end thereof, a supplemental block adjustably supported in connection with the other end of the first named block, a yoke-shaped arm arranged at one side of the block and coupled with the supplemental block to provide swinging movement of the arm with respect to the first named block, the free end of said arm having a work-piece supporting part arranged in close proximity to said member, means for adjusting said arm longitudinally of the supplemental block to adjust the part thereon toward and from said member, and another work-piece supporting element adjustably supported in connection with the first named block and tensionally movable therein to aid in supporting a work-piece in connection with said member and part.

20. An attachment for use in supporting the sole and upper in the operation of stitching the same together, said attachment comprising a block, means for adjustably mounting said block in a suitable support, means at the outer end of the block for supporting the sole and upper in engagement in stitching the same together, said means comprising two relatively adjustable disc-like members arranged with the surfaces of said members in opposed relationship, one of said members being adjustable toward and from the other to regulate the spacing and alinement of said members, and one of said members forming a spreader for part of the sole in the operation of stitching the upper thereto.

ALEXANDER SOLTAN.
